ENGINE FRAME

Edwin S. Hall, Farmington, Conn., assignor to
 Rogers Diesel and Aircraft Corporation, New
 York, N. Y., a corporation of New York

Application April 14, 1945, Serial No. 588,323

20 Claims. (Cl. 123—58)

1

This invention relates to engine frames in general and more specifically to cylinder block constructions for opposed-piston internal combustion engines. The invention may be applicable to all such engines but it will be described as applied to an engine of the class commonly called barrel type, axial, or round engines, the class having cylinders parallel to the shaft.

Either the cylindrical cam and roller mechanism, or one of the several swashplate mechanisms may be used in such an engine. The cylinder block may include a group of cylinders spaced about and parallel to the engine shaft, between a pair of cams or a pair of plate mechanisms on the same shaft. Cross-head guides coaxial with the several cylinders may be provided for the reciprocating members of the two mechanisms.

The object of the invention is to provide an engine frame construction or cylinder block of low cost in production, consisting essentially of stampings and tubes press-fitted together and furnace brazed into a single unit. Another object of the invention is to provide a strong and lightweight frame structure for an opposed-piston barrel engine. Another object is to provide a cylinder block construction for an opposed-piston barrel engine in which the manifold walls are included in the block itself.

Another object is to provide a frame structure in which a series of identical stampings may be used to form hollow bulkheads to serve as water manifolds. Another object is to provide a frame structure for an opposed-piston barrel engine in which the water flow thru the cylinder jackets may be properly directed by the construction of the block itself. Another object is to provide a cylinder block construction in which the fuel nozzle or precombustion chamber may be removed without draining the cooling water. Other objects are to provide for separate flow of the coolant thru the nozzle holder or precombustion chamber cover, and to provide convenient means for closing off this separate flow of the coolant when it is desired to remove the nozzle holder or precombustion chamber.

A further object is to provide a cylinder block construction for an opposed-piston barrel engine in which the exhaust from each cylinder may be directed tangentially into a circumferential manifold so that each exhaust may aid in scavenging the other cylinders. Fairing in such a manifold may be corroded by the sulphurous exhaust content. Another object is to provide easily replace-

2

able cast fairing for directing the exhaust from each cylinder into the exhaust manifold.

Another object is to provide a construction for an opposed-piston barrel engine in which the cylinder block is short, independent of the cross-head guide sections which may be removed leaving the reciprocating members and the conversion mechanisms substantially intact in position for inspection and adjustment. Another object is to provide a short cylinder block of such low cost that it may be considered the replaceable member, obviating the need for individual replaceable cylinder liners.

These and other objects will be more apparent from the following description in connection with the drawings in which:

Figure 1 is a longitudinal section thru the improved engine frame, showing the cylinder block and one of the two crosshead guide portions;

20 Fig. 2 is a plan view of one of the stampings used in the construction of the frame of Fig. 1;

Fig. 3 is a section on the line 3—3 of Fig. 2;

Fig. 4 is a transverse section on the line 4—4 of Fig. 1;

25 Fig. 5 is a top view of the adjacent portion of Fig. 1; and

Fig. 6 is a section on the line 6—6 of Fig. 5.

Referring to the drawings, each cylinder liner 10 may be cast or otherwise formed with intake ports 11 and exhaust ports 12, and with longitudinal cooling fins 13 in its central combustion region. Water passages 19 may be drilled or cored thru each of the bridges between ports 11 and ports 12. The outer periphery of the port rings 30 and fins 13 may be turned down to a given diameter to fit inside sleeves 14 and 15, the inside bore of these sleeves being the same as that of crosshead guides 45. End rings 16 fitting the ends of cylinder liner 10 and fitting inside sleeves 15 35 serve to close the ends of water jacket 18 surrounding each liner 10.

The parts 10—19 inclusive thus form an individual "cylinder liner" of known structure, ordinarily assembled in a "block" in a removable manner so that any one liner becoming damaged may be easily replaced. It would be possible to form the frame of the present invention to permit easy removal of these liners, but I prefer to add a water-jacket for a nozzle holder or precombustion chamber extending radially from each liner, and then assemble the set of liners in a series of bulkheads formed of stampings, brazing the assembly to form a short cylinder block of low enough cost to permit considering the whole block replaceable.

Tubular jacket 24 is fitted into a radial bore in sleeve 14, and inner jacket 20 is fitted into a smaller radial bore in liner 10 its upper lip fitting the interior of tubular jacket 24. Two holes 23 may be provided in jacket 24, and the adjacent sides of jacket 24 may be flattened. When the several cylinder assemblies have been put together with copper or other suitable brazing material near each joint, flat stampings 30 in pairs, each stamping 30 having upturned edges 36 forming a hollow bulkhead 33, may be similarly assembled with inter-cylinder water pipes 39 in place. Between the two inner bulkheads 33, adjacent each of the radial jackets 24, a transfer pipe 22 may be inserted. The coolant chambers comprising jackets 18, passages 19, bulkheads 33, and pipes 39 may include also the annular space 28 between tubes 27 and 29 which house the central shaft (not shown). Space 28 may be closed at the ends by rings 26 which may help in supporting inner main bearings for the shaft. Half-holes 32 formed in the up-turned edges 36 of stampings 30 permit the coolant to flow to and from pipes 39, bulkheads 33, annular chamber 28, and jackets 18. For circulation and drainage of coolant thru the annular space between jackets 24 and 20, holes 23 are provided. Reinforcing plates 37 may be added at each end of the block assembly, and rings 31 may surround each bulkhead and provide grooves for suitable packing to seal the surrounding closure (not shown). The entire cylinder block assembly may be furnace-brazed, heat-treated and finished as a unit.

Thereafter precombustion chamber 50 may be inserted in its jacket 20 for each cylinder, and its cover 51 may be fastened with suitable gasket packing by suitable screws as indicated in Figs. 1 and 5. Plug cock 52 fits a bore in transfer pipe 22, and may be clamped to cover 51 by screw 53. When in the position shown, plug cock 52 directs the flow from one bulkhead 33 into cover 51 and around the nozzle (not shown) and out again thru transfer pipe 22 to the other bulkhead 33. When it is desired to remove cover 51 or pre-combustion chamber 50, screw 53 may be loosened, and plug cock 52 turned to close both ends of transfer pipe 22. Then the screws may be removed and cover 51 taken off losing only the small amount of coolant contained in cover 51, without the necessity for draining the whole system.

After assembly of the reciprocating parts, and the conversion mechanism (not shown), at each end of the cylinder block, a crosshead guide section is added. One such section only is shown in Fig. 1, it being understood that another will be used at the left end of the cylinder block. Each crosshead guide section includes the several crosshead guides 45 coaxial with cylinder liners 10 and held together by another bulkhead 33 comprising a pair of stampings 30 with their outer ring 31. Reinforcing plate 47 may mate with plate 37 of the cylinder block, and end plate 48 may aid in supporting the ring 46 in which an outer main bearing might be mounted.

The air manifold to direct the scavenge air to intake ports 11 of the several cylinders is formed by the two bulkheads 33 at the left of the cylinder block in Fig. 1, and the exhaust manifold is formed by the two bulkheads 33 at the right. In the latter, a series of half-rings 60 of U-section, conveniently formed as malleable iron castings, may be swung into place, after which the outer fairing sectors 61, also castings, may be inserted radially into the manifold as shown in Figs. 1 and

4, these parts being held in by the outer closure (not shown) to be wrapped around the entire structure. It is obvious from Fig. 4 that the burst of exhaust from each cylinder as thru the nozzle 65 will aid in the rapid circumferential flow of the exhaust in the passage 66, this flow aiding in the promotion of the scavenge of each cylinder. It is understood that a tangential take-off or exhaust pipe will be provided at a convenient point around the circumferential passage 66.

Having thus described the invention it is clear that the objects thereof as stated have been attained. While a specific embodiment has been shown and described, it is understood that changes may be made in the construction and in the arrangement of the invention without departing from the spirit or scope of the invention as expressed in the following claims.

I claim:

1. In an opposed-piston engine, a cylinder block comprising a series of hollow bulkheads spaced apart and each formed from a pair of substantially identical stampings placed face to face, a set of holes thru each of said bulkheads, and a series of cylinder members extending thru said holes and connecting said bulkheads, the assembly of bulkheads and cylinder members brazed into an integral cylinder block.

2. In an opposed-piston engine, a cylinder block comprising a series of hollow bulkheads spaced apart and each formed from a pair of substantially identical stampings placed face to face, a set of holes thru each of said bulkheads, and a series of cylinder members each having its own water jacket and extending thru said holes and connecting said bulkheads, said bulkheads formed as water manifolds to direct coolant into and out of said water jackets, the assembly of bulkheads and cylinder members brazed into an integral cylinder block.

3. In an opposed-piston barrel engine, a cylinder block comprising a series of hollow bulkheads spaced apart and each formed from a pair of substantially identical circular stampings placed face to face, a central hole and a series of holes spaced about said central hole thru each of said bulkheads, and tubular members extending thru said holes and connecting said bulkheads, the assembly of bulkheads and tubular members brazed into an integral cylinder block.

4. In an opposed-piston barrel engine, a cylinder block comprising two pairs of hollow bulkheads, one pair spaced apart to form an air manifold between them and the other pair spaced apart to form an exhaust manifold between them, each bulkhead formed from a pair of substantially identical circular stampings placed face to face, a set of holes thru each of said bulkheads, and a series of cylinder members extending thru said holes and connecting said bulkheads, said cylinder members having air ports opening into said air manifold and exhaust ports opening into said exhaust manifold, the assembly of bulkheads and cylinder members brazed into an integral cylinder block.

5. In an opposed-piston barrel engine, a cylinder block comprising two pairs of hollow bulkheads, one pair of spaced apart to form an air manifold between them and the other pair spaced apart to form an exhaust manifold between them, each bulkhead formed from a pair of substantially identical circular stampings placed face to face, a set of holes thru each of said bulkheads, and a series of cylinder members each having

its own water jacket and extending thru said holes and connecting said bulkheads, said cylinder members having air ports opening into said air manifold and exhaust ports opening into said exhaust manifold, each hollow bulkhead forming a water manifold to direct coolant into and out of said water jackets, the assembly of bulkheads and cylinder members brazed into an integral cylinder block.

6. In an opposed-piston barrel engine, a cylinder block comprising two pairs of hollow bulkheads, one pair spaced apart to form an air manifold between them and the other pair spaced apart to form an exhaust manifold between them, a similar set of holes thru each of said bulkheads, and a series of cylinder members extending thru said holes and connecting said bulkheads, each of said cylinder members having air ports opening into said air manifold and exhaust ports opening into said exhaust manifold and a water jacket opening into said hollow bulkheads.

7. In an opposed-piston barrel engine, a cylinder block comprising two pairs of hollow bulkheads, one pair spaced apart to form an air manifold between them and the other pair spaced apart to form an exhaust manifold between them, a similar set of holes thru each of said bulkheads, and a series of cylinder members extending thru said holes and connecting said bulkheads, each of said cylinder members having air ports opening into said air manifold and exhaust ports opening into said exhaust manifold and a water jacket opening into said hollow bulkheads, the assembly of bulkheads and cylinder members brazed into an integral cylinder block; in combination with removable fairing in said exhaust manifold for directing the flow of exhaust from each of said cylinders independently into said manifold.

8. In an opposed-piston barrel engine, a cylinder block comprising two pairs of hollow bulkheads, one pair spaced apart to form an air manifold between them and the other pair spaced apart to form an exhaust manifold between them, a similar set of holes thru each of said bulkheads, and a series of cylinder members extending thru said holes and connecting said bulkheads, each of said cylinder members having air ports opening into said air manifold and exhaust ports opening into said exhaust manifold and a water jacket opening into said hollow bulkheads, the assembly of bulkheads and cylinder members brazed into an integral cylinder block; in combination with removable fairing in said exhaust manifold for directing the flow of exhaust from each of said cylinders independently into said manifold, said fairing formed to provide a circumferential manifold passage with the exhaust from each cylinder entering it tangentially from within as thru a jet to promote continuously rapid flow of exhaust in said manifold passage.

9. In an opposed-piston barrel engine, a cylinder block comprising four hollow bulkheads, a similar set of holes thru each bulkhead, and cylinder members extending thru said holes and connecting said bulkheads, the first two bulkheads spaced apart and forming an air manifold, the last two bulkheads spaced apart and forming an exhaust manifold, each of said hollow bulkheads forming a water manifold, each of said cylinder members having air ports opening into said air manifold and exhaust ports opening into said exhaust manifold and a water jacket with ports opening into said hollow bulkheads.

10. In an opposed-piston barrel engine, a cyl-

inder block comprising four hollow bulkheads, a similar set of holes thru each bulkhead, and cylinder members extending thru said holes and connecting said bulkheads, the first two bulkheads spaced apart and forming an air manifold, the last two bulkheads spaced apart and forming an exhaust manifold, each of said hollow bulkheads forming a water manifold, each of said cylinder members having air ports opening into said air manifold and exhaust ports opening into said exhaust manifold and a water jacket with ports opening into said hollow bulkheads, the two inner bulkheads spaced apart, and a nozzle holder extending radially from each of said cylinders into the space between said inner bulkheads.

11. In an opposed-piston barrel engine, a cylinder block comprising four hollow bulkheads, a similar set of holes thru each bulkhead, and cylinder members extending thru said holes and connecting said bulkheads, the first two bulkheads spaced apart and forming an air manifold, the last two bulkheads spaced apart and forming an exhaust manifold, each of said hollow bulkheads forming a water manifold, each of said cylinder members having air ports opening into said air manifold and exhaust ports opening into said exhaust manifold and a water jacket with ports opening into said hollow bulkheads, the two inner bulkheads spaced apart, and a precombustion chamber extending radially from each of said cylinders into the space between said inner bulkheads, a water jacket for said chamber, and ports connecting said chamber jacket with said inner hollow bulkheads.

12. In an opposed-piston barrel engine, a cylinder block comprising four hollow bulkheads, a similar set of holes thru each bulkhead, and cylinder members extending thru said holes and connecting said bulkheads, the first two bulkheads spaced apart and forming an air manifold, the last two bulkheads spaced apart and forming an exhaust manifold, each of said hollow bulkheads forming a water manifold, each of said cylinder members having air ports opening into said air manifold and exhaust ports opening into said exhaust manifold and a water jacket with ports opening into said hollow bulkheads, the two inner bulkheads spaced apart, and a precombustion chamber extending radially from each of said cylinders into the space between said inner bulkheads, a water jacket for said chamber, ports connecting said chamber jacket with said inner hollow bulkheads, a separable cover for said chamber, a water jacket in said cover, a bypass for coolant between said inner bulkheads adjacent said cover, and means for directing coolant from said bypass into and thru said cover jacket.

13. In an opposed-piston barrel engine, a cylinder block comprising four hollow bulkheads, a similar set of holes thru each bulkhead, and cylinder members extending thru said holes and connecting said bulkheads, the first two bulkheads spaced apart and forming an air manifold, the last two bulkheads spaced apart and forming an exhaust manifold, each of said hollow bulkheads forming a water manifold, each of said cylinder members having air ports opening into said air manifold and exhaust ports opening into said exhaust manifold and a water jacket with ports opening into said hollow bulkheads, the two inner bulkheads spaced apart, and a precombustion chamber extending radially from each of said cylinders into the space between

said inner bulkheads, a water jacket for said chamber, ports connecting said chamber jacket with said inner hollow bulkheads, a separable cover for said chamber, a water jacket in said cover, a bypass for coolant between said inner bulkheads adjacent said cover, and adjustable means for either directing coolant from said bypass into and thru said cover jacket or for closing off all flow of coolant thru or out of said bypass to permit removal and replacement of said cover and said precombustion chamber without draining the coolant from said cylinder block.

14. In an opposed-piston barrel engine, a cylinder block comprising a series of hollow bulkheads spaced apart, a similar set of holes thru each of said bulkheads, and a series of parallel tubular members extending thru said holes and connecting said bulkheads; said tubular members including an axial housing, cylinder members spaced about said housing, and water pipes alternating with said cylinder members; each of said cylinder members having a water jacket, and ports in said jackets and in said water pipes, said ports opening into said hollow bulkheads.

15. A frame construction for an opposed-piston barrel engine comprising a pair of similar frame portions and a cylinder block between them and coaxial therewith, said frame portions and cylinder block each comprising a plurality of bulkheads spaced apart, a similar set of holes thru each bulkhead, and a series of parallel tubular members extending thru said holes and connecting said bulkheads, said tubular members in said frame portions coaxial with those of said cylinder block.

16. A frame construction for an opposed-piston barrel engine comprising a pair of similar frame portions and a cylinder block between them and coaxial therewith; said cylinder block comprising a series of bulkheads spaced apart, a similar set of holes thru each of said bulkheads, and a series of parallel cylinder members extending thru said holes and connecting said bulkheads; each of said frame portions including similar bulkheads with similar holes therein and a series of cylindrical crosshead guides extending thru said holes and connecting said bulkheads, said crosshead guides coaxial with said cylinder members.

17. A frame construction for an opposed-piston barrel engine comprising a pair of similar frame portions and a cylinder block between them and coaxial therewith; said cylinder block comprising a series of hollow bulkheads, two of said bulkheads spaced apart to form an air manifold and two of said bulkheads spaced apart to form an exhaust manifold, a similar set of holes thru each bulkhead, and cylinder members extending thru said holes and connecting said bulkheads, each of said cylinder members having air ports opening into said air manifold and exhaust ports opening into said exhaust manifold and a water jacket with ports opening into said hollow bulkheads; each of said frame portions including similar bulkheads with similar holes therein and

a series of cylindrical crosshead guides extending thru said holes and connecting said bulkheads, said crosshead guides coaxial with said cylinder members.

18. A frame construction for an opposed-piston barrel engine comprising a pair of similar frame portions and a cylinder block between them and coaxial therewith; said cylinder block comprising a series of hollow bulkheads, a similar set of holes thru each of said bulkheads, and a series of parallel tubular members extending thru said holes and connecting said bulkheads, said tubular members including an axial housing and cylinder members spaced about said housing and water pipes alternating with said cylinder members; each of said frame portions including similar bulkheads with similar holes therein and tubular members extending thru said holes and connecting said bulkheads, said last-named tubular members including cylindrical crosshead guides coaxial with said cylinder members and water pipes coaxial with the water pipes of said cylinder block and connecting therewith.

19. A frame construction for an opposed-piston barrel engine comprising a pair of similar frame portions and a cylinder block between them and coaxial therewith; said cylinder block comprising a series of hollow bulkheads, a similar set of holes thru each of said bulkheads, and a series of parallel tubular members extending thru said holes and connecting said bulkheads; said tubular members including an axial double-walled housing having an annular water chamber, cylinder members spaced about said housing and each having a water jacket, and water pipes alternating with said cylinder members; each of said frame portions including bulkheads with holes therein and tubular members extending thru said holes and connecting said bulkheads; said last-named tubular members including cylindrical crosshead guides coaxial with said cylinder members, and water pipes coaxial with the water pipes of said cylinder block; and ports in said water pipes and said cylinder water jackets and said annular water chamber, said parts opening into said hollow bulkheads.

20. In an opposed-piston barrel engine, a cylinder block comprising four hollow bulkheads, a similar set of holes thru each bulkhead, and tubular members extending thru said holes and connecting said bulkheads, the first two bulkheads spaced apart and forming an air manifold, the last two bulkheads spaced apart and forming an exhaust manifold, each of said hollow bulkheads forming a water manifold; and said tubular members including a central housing coaxial with said block and having an annular jacket with ports opening into said hollow bulkheads, cylinder members each having air ports opening into said air manifold and exhaust ports opening into said exhaust manifold and a water jacket with ports opening into said hollow bulkheads, and water pipes having ports opening into some of said hollow bulkheads.
